DESIGN FOR A CHAIR ARM

William L. Gittings, Racine, Wis., assignor to
Gold Medal Folding Furniture Co., Racine,
Wis., a corporation of Wisconsin

Application April 30, 1936, Serial No. 62,385

Term of patent 14 years

To all whom it may concern:

Be it known that I, William L. Gittings, of Racine, in the county of Racine and State of Wisconsin, have invented a new, original, and ornamental Design for a Chair Arm, of which the following is a specification, reference being had to the accompanying drawing, forming part thereof.

In the drawing:

The figure is a perspective view of the article illustrating my new design, the distinctive features of which consist in the stream-line contour

of the base rail, and the distinctive shape of the tilted rear upright flared from its lower end, terminating in an intermediate shoulder from which a tapered spindle projects and is provided with a top spherical knob.

I claim:

The ornamental design for a chair arm, as shown and described.

In testimony that I claim the foregoing I have hereunto set my hand, at Racine, in the county of Racine and State of Wisconsin.

WILLIAM L. GITTINGS.
